UNITED STATES PATENT OFFICE.

WILLIAM D. STROUD, OF OSHKOSH, WISCONSIN.

CULTIVATOR-TOOTH.

SPECIFICATION forming part of Letters Patent No. 258,263, dated May 23, 1882.

Application filed February 14, 1882. (Model.)

To all whom it may concern:

Be it known that I, Wm. D. STROUD, of Oshkosh, Winnebago county, Wisconsin, have invented certain Improvements in Cultivators or Cultivator-Teeth, of which the following is a specification.

The nature of my invention relates to the use of a cultivator tooth or blade so attached to the shank as to be flexible or yielding when the blade strikes a stone or other obstruction.

It further relates to a device for changing and adjusting the lateral angle of the blade so as to throw the earth to the right or the left at will.

It further relates to a combination of the two devices mentioned, which together form a universal joint, by which both the longitudinal and lateral position of the blade may be changed, all of which will be more readily understood by reference to the drawings, in which—

Figure 1 is a side elevation of the cultivator-tooth, and Fig. 2 is an enlarged section on *a b*.

A is the shank. K is a yoke, the extremities of which span over the end of the shank and are attached thereto by a pivot, I. The shoulder of the yoke passes round the wrist G, which is firmly attached to the blade H. The spring B is attached to the shank A by a stirrup, D, and key C. The lower end of the spring 30 engages a link, E, the other end of which is

engaged by the projecting end F of the wrist G on the blade, and it will be readily seen that the blade may assume the position indicated by the dotted lines in Fig. 1, or any other intermediate between that and the full lines. 35 The wrist G, to which the blade is attached, may have a dressed face or key-seat, as shown in Fig. 2, and a gib, S, inserted and fastened in position by a key, L. By reversing the ends of the gib S the blade will assume the position 40 shown by the dotted lines in Fig. 2.

To fasten the blade laterally in a horizontal position a gib, S', may be used instead of S.

It is understood that I do not claim an elastic cultivator-tooth, as such, but the devices by 45 which the elasticity is attained.

I claim—

1. The combination of the cultivator-tooth H, key-seated wrist G, and gib S with the pivoted yoke K, substantially as shown and described. 50
2. The cultivator-tooth H, having a key-seated wrist, G, and gib S, in combination with the pivoted yoke K, link E, and spring B, substantially as and for the purpose shown and described.

WILLIAM D. STROUD.
